UNITED STATES PATENT OFFICE.

HARRY WOLF KULP AND MARTIN COPE DELLINGER, OF LANCASTER, PENNSYLVANIA.

VALVE-SPRING LIFTER.

1,359,814.

Specification of Letters Patent. Patented Nov. 23, 1920.

Application filed October 21, 1919. Serial No. 332,161.

To all whom it may concern:

Be it known that we, HARRY WOLF KULP and MARTIN COPE DELLINGER, citizens of the United States, residing at Lancaster, in 5 the county of Lancaster and State of Pennsylvania, have invented certain new and useful Improvements in Valve-Spring Lifters, of which the following is a specification.

The present invention relates to valve 10 spring lifters. Devices of this general class are designed more especially for use in removing the valves from internal combustion engines. To remove the valves it is necessary to compress and lift the valve 15 spring so that the pin or other spring holding means may be removed from the stem. Spring lifters heretofore in use have been, for the most part, plier-like tools comprising two pivotally connected jaw carrying 20 arms or levers, the lower jaw being made to bear on a fixed base, while the upper jaw will bear against the lower end of the valve spring; or the jaws may bear respectively on the upper and lower ends of the spring. 25 In the first case the tool is operated to open or separate the jaws, causing compression of the spring by upward movement of the jaw in contact with the lower end of the spring; and in the second case the spring 30 will be compressed between the jaws as they are closed.

But the great objection to tools of this class is the lack of parallelism between the jaws during their operation. They swing 35 from the point of pivotal connection between the levers or arms. Consequently, during operation they are not parallel, but at an angle to each other. Consequently, the jaws will not act with evenness on the 40 spring in a line parallel to the valve stem, but will compress it more on one side than on the other.

The chief object of the present invention is to insure the absolute parallelism of the 45 jaws of the tool in every position. Another object is to provide a simple, efficient, compact tool which may be produced at a moderate cost. Further objects will appear from the following detailed description and 50 claims.

In the drawings:

Figure 1 is a side elevation of the invention.

Fig. 2 is a top plan view, and

55 Fig. 3 is a cross section on line $x-x$ of Fig. 1.

In order to provide the desired simplicity and at the same time insure the desired parallelism in the travel of the jaws, a stationary jaw-carrying arm coöperating with a 60 movable jaw-carrying beam is provided, the two being flexibly connected by a pair of pivotally connected links, one end of each link being pivotally connected to each jaw-carrying member, while the opposite end of 65 each has a sliding pivotal connection with the other jaw-carrying member, and a movable handle being formed in extension of one of said links.

Preferably the stationary arm 1 is substantially U-shaped in cross section, carrying the jaw 2 at one end and being provided with parallel elongated openings or slots 3 in its opposite walls, about midway of its length, for a purpose to be later disclosed. 70 Also, for a purpose to be later disclosed, the bottom of the U of arm 1 is cut away, as at 4, below the bolts 3. Coöperating with stationary arm 1 is a short movable beam 6, also of substantially U-shaped cross section 80 and carrying a jaw 5 coöperating with jaw 2. It is similarly slotted at 7 and cut away at 8, the parts being so proportioned and arranged that when the jaws are superposed one upon the other and the beam upon the 85 arm the slots 7 will be directly above the slots 3. A link 9 has a fixed pivotal connection at one end with the forward part of arm 1 by means of a fixed pivot pin 10 passed through the walls of arm 1 and the 90 lower end of the link therebetween. The other or upper end of the same link has a free sliding pivotal connection with the rear end of beam 6 by means of a pivot pin 11 passed through that end and sliding freely 95 in slots 7, one end of said pin extending slightly beyond one outer wall of the beam for a purpose to be later disclosed. A second and similar link 12 has its upper end pivotally connected to the forward end of beam 6 by a fixed pivot pin 13 passed through the walls of beam 6 and the upper end of the link. The lower end has a sliding pivotal connection with the arm 1 by means of a pivot pin 14 passed through the 100 lower end of the link and sliding freely in the slots 3. The two links are pivotally connected to each other by a pin 15 passed through their centers, or at the point of their intersection. The links thus arranged 105 provide a lazy tong construction for operating jaws 2 and 5, so that as they are forced

open or toward a substantially horizontal position the jaws 2 and 5 will be drawn toward each other, while forcing them in the opposite direction or toward a substantially vertical position will separate or open jaws 2 and 5. To effect these movements an elbow arm 16 is provided. It is formed in continuation of the rear lower end of link 12. Thus, while the lower end of the arm 16 lies between the wall of the arm 1, the upper rear portion providing a hand grip is considerably spaced from and lies directly above the hand grip or rear portion of arm 1. Thus it will be seen that the jaws 5 are operated by a lazy tong construction, which makes it impossible for them to assume any other than an exactly true parallel relation one to the other and positively insures this relation throughout the travel of jaw 5. The means for actuating the lazy tong, of course, is the elbow arm 16. By forcing it toward arm 1 the lazy tong will be contracted or closed, the upper and lower ends of the links respectively being made 25 to approach each other, but being kept at the same distances from their centers by the fixed pivot 15, thus compelling absolute parallelism between beam 6 and arm 1 and their jaws throughout the travel of beam 6. 30 Of course, by moving arm 16 in the opposite direction, or away from arm 1, the opposite action of the lazy tong will result, moving jaws 2 and 5 toward each other. The cut out portions 4 and 8 facilitate access to the sliding pivot connections, permit 35 perfectly free and uninterrupted travel of the sliding link ends, and to a certain degree lighten the device.

It may be desired to temporarily lock the jaws in their extreme open position. For this purpose a locking plate 17 is provided having a slot or opening 18 co-extensive with slot 7. At the forward end a notch 19 extends upwardly and rearwardly from slot 45 18, providing a downwardly and forwardly directed curved shoulder 20. The forward end of the plate is pivoted on the pivot pin 13 while the pivot pin 11 travels freely in slot 18, the plate being so proportioned and positioned that slot 18 is superposed on slot 7. Now, as pivot pin 11 reaches the extreme forward point of its travel in slots 7 and 18, it will come directly in line with the entrance to notch 19. Plate 17 immediately 50 drops by gravity, so that pivot pin 11 becomes seated in notch 19, with the shoulder 20 extending below and behind the pivot pin and preventing any return movement thereof in slot 18. Various changes may be made 55 in the construction and arrangements of different parts without in any sense departing from the scope of the invention, and it is meant to include all such within the following claims.

Having thus described our invention,

what we claim and desire to secure by Letters Patent is:

1. A valve spring lifting tool comprising a jaw carrying member having a handle in continuation thereof, a short jaw-carrying beam coöperating therewith and extending, substantially, half the length of the first member from the jaw end toward the handle, a pair of crossed links, fixed pivotal connections between one end of each link and one of said jaw-carrying members, fixed pivotal connections between said links at their point of intersection, sliding pivotal connections between the other end of each link and each jaw-carrying member, and a handle connected to and extending at an angle from one of said links.

2. A valve spring lifting tool comprising a jaw-carrying member having a handle in alinement and in continuation thereof, a short jaw-carrying beam coöperating therewith, a lazy-tong, fixed pivotal connection between one end of each member of said lazy-tong and one of the jaw-carrying members, sliding pivotal connection between the opposite end of each member of said lazy-tong and one of the jaw-carrying members, and an elbow arm formed in continuation of one of said lazy-tong members.

3. A valve spring lifting tool comprising a jaw-carrying member having a handle in alinement and in continuation thereof, a short jaw-carrying beam coöperating therewith, a lazy-tong, fixed pivotal connection between one end of each member of said lazy-tong and one of the jaw-carrying members, sliding pivotal connection between the opposite end of each member of said lazy-tong and one of the jaw-carrying members, an elbow arm formed in continuation of one of said lazy-tong members, and a movably mounted locking plate adapted to automatically engage one of said sliding pivotal connections to secure the jaws in open position.

4. A valve spring lifting tool comprising coöperating jaw-carrying members, a pair of connected links, connections between each of said links and both of said jaw-carrying members, means for moving said movable jaw-carrying member relatively to said stationary jaw-carrying member, and gravity actuated means for securing said jaw-carrying members in an open position.

5. A valve spring lifting tool comprising a jaw-carrying member having a handle in alinement and in continuation therewith, a short jaw-carrying beam coöperating therewith, a lazy-tong, fixed pivotal connection between one end of each member of said lazy-tong and one of the jaw-carrying members, sliding pivotal connection between the opposite end of each member of said lazy-tong and one of the jaw-carrying members, an elbow arm formed in continuation of one of said lazy-tong members, and a locking

plate pivotally mounted on said jaw-carrying beam and provided with a slot for the free travel of one of said sliding pivotal connections, said slot terminating in a notch 5 forming a shoulder adapted to drop behind and engage said pivotal connection to automatically lock said jaws in open position.

6. A valve spring lifting tool comprising coöperating jaw-carrying members, a pair 10 of connecting links, connections between each of said links and both of said jaw-carrying members, means for moving said movable jaw-carrying member relatively to said stationary jaw-carrying member, and a 15 locking plate adapted to engage one of the connections of said links to lock said jaw-carrying members in an open position.

7. A valve spring lifting tool comprising coöperating jaw-carrying members, a pair of 20 connected links, fixed pivotal connections between one end of each of said links and one of said members, sliding pivotal connections between the other end of each of said links and the other of said members, 25 and a pivotally mounted plate adapted to engage one of said pivotal connections to secure said jaw-carrying members in an open position.

8. A valve spring lifting tool comprising 30 coöperating jaw-carrying members, means for flexibly connecting said jaw-carrying members, an elbow lever arm formed in continuation of one element of said connecting means, and sliding pivotal connections between 35 said elbow lever arm and one of said jaw carrying members.

9. A valve spring lifting tool comprising coöperating jaw-carrying members, means for flexibly connecting said jaw carrying 40 members, an elbow lever arm formed in continuation of one element of said connecting means, sliding pivotal connections between said elbow lever arm and one of said jaw carrying members, and means for automatically 45 securing said jaw carrying members in open position.

10. A valve spring lifting tool comprising 50 jaw-carrying members, means for flexibly connecting said jaw-carrying members, means for maintaining parallel relation be-

tween said jaw-carrying members at all times, and an operating lever arm carried by one element of said connecting means.

11. A valve spring lifting tool comprising a jaw-carrying member, a relatively short 55 jaw-carrying beam coöperating therewith and movable relatively thereto, a link having fixed pivotal connection at one end to said stationary member and sliding pivotal connection at its opposite end to said beam, a second link intersecting the first and having fixed pivotal connection thereto at such point of intersection and also having fixed pivotal connection at one end to one end of said beam and sliding pivotal connection at its opposite end to said stationary member, and an operating lever handle formed in continuation of said second link. 60

12. A valve spring lifting tool comprising coöperating jaw-carrying members, means 70 for operating said members, means for flexibly connecting said jaw-carrying members, and a locking device carried by one of said members and adapted to engage an element of said connecting means to automatically 75 lock said members in open position.

13. A valve spring lifting tool comprising jaw carrying members, means for flexibly connecting said jaw carrying members, means for maintaining parallel relation between 80 said jaw carrying members at all times, an operating lever arm carried by one element of said connecting means, and means for automatically securing said jaw carrying members in open position. 85

14. A valve spring lifting tool comprising a jaw and a handle integral therewith, in combination with a movable jaw, means for connecting said latter jaw and said handle in order to maintain said jaws in parallel 90 relation in all positions, and a second handle connected to said means to actuate the same.

In testimony whereof, I have signed my name to this specification in the presence of two subscribing witnesses.
